UNITED STATES PATENT OFFICE.

HENRY S. STEVENS, OF KEENE, NEW HAMPSHIRE.

PERPETUAL CALENDAR.

SPECIFICATION forming part of Letters Patent No. 534,726, dated February 26, 1895.

Application filed October 20, 1894. Serial No. 526,436. (No model.)

To all whom it may concern:

Be it known that I, HENRY S. STEVENS, a resident of Keene, in the county of Cheshire and State of New Hampshire, have invented 5 certain new and useful Improvements in Perpetual Calendars; and I do hereby declare the following to be a full, clear, and exact description of the invention, such as will enable others skilled in the art to which it appertains 10 to make and use the same.

My invention relates to an improvement in calendars and more particularly to such as are known as perpetual calendars,—the object 15 of the invention being the production of a simple perpetual calendar, by means of which the day of the week of a given date can be readily, quickly and accurately ascertained.

With this object in view the invention consists in certain novel features of construction 20 and combinations and arrangements of parts as hereinafter set forth and pointed out in the claims.

In the accompanying drawings: Figure 1 is a view showing the appearance of my improved calendar when open. Figs. 2, 3, 4, 5, 25 6, 7, and 8 are views of the various tables having the days of the week and years marked thereon. Fig. 9 is a view illustrating a modification.

30 X represents a cover of heavy paper or any other suitable material, in which two books or series of leaves 1, 2, are secured, the book or leaves 1 being secured to the cover at the junction of the sides thereof and having the 35 names of the months and the days of the month produced thereon, two adjacent pages being devoted to each month as illustrated in Fig. 1. The book 1 overlaps all of book 2 except the days thereon which it leaves exposed 40 secured at its center to the inner face of one side of the cover. On each two adjacent pages of the book 2 a table is produced. In the drawings each table is divided into five columns or spaces A, B, C, D, E. In the column 45 or space A the names of the days of the week are produced. In the column or space B, figures indicating certain years of one century (the nineteenth, for instance) are produced and in the columns or spaces C, D, E, figures 50 indicating certain years in succeeding centuries are made. The pages of the book 2 are so disposed that the names of the days of the

week on any page can be read with the days of the month on any page of the book 1, as 55 illustrated in Fig. 1. The various tables are shown in Figs. 2, 3, 4, 5, 6, 7 and 8 and are lettered a, b, c, d, e, f and g, said tables corresponding in number with the number of the days of the week. In column A of table a the days of the week are produced commencing 60 with Saturday and in column A of table b the days of the week are produced beginning with Sunday and so on throughout the series of tables so that the days of the week can be read 65 in regular order across the series of tables. 65

The same day of the week corresponding with a given day of the month will recur once in six years and the years will be arranged in the vertical columns in the various tables counting by six in each column until a leap 70 year or a year divisible by four without a remainder is reached. For instance, the first year in the column B of table e is 1800, the next 1806 and the next 1812, which latter was leap year and is underscored. In the months 75 January and February, 1812, certain days of the month fell on Wednesday, but as an additional day is added to the month of February in leap year, days of the month after February which would otherwise fall on Wednesday, will occur a day later in the week, viz: Thursday and for this reason the year 1812 will be duplicated in the column B of the next 80 table opposite the word "Thursday" and will then be marked with a star to indicate that 85 when it is desired to find out on what day of the week a certain day of the month occurred, the page containing the leap year marked with a star must be used,—the table containing the 90 leap year with the underscore being used for the months of January and February. Thus by using the arrangement of table e, it will be seen that the first day of January, 1812, occurred on Wednesday. Were this arrangement in table e used for a month succeeding 95 February, say for example October, it would indicate that October 1 occurred on Wednesday which would be incorrect, because the occurrence of February 29, 1812, would cause October 1 to come one day later in the week 100 than it otherwise would. By using the arrangement in table f, it will indicate that October 1, 1812, occurred on Thursday. The year 1812 being leap year, the next year in

dicated in column B of table *e* will be five years later instead of six, viz: 1817. After 1817, 1823 (six years later) is indicated in column B table *e*. After 1823, 1828 is placed in 5 column B, 1828 being a leap year indicated in a corresponding position in column B table *d* and is marked with a star. After 1828, 1834 (six years later) appears in column B table *e*.

The manner above explained of arranging 10 the years will be followed throughout the calendar and will be found to be accurate.

To ascertain on what day of the week a certain predetermined day of the month in a certain year occurs, the following directions 15 should be observed: Find the year required. On the left will be the days of the week for that year except leap years which have two places. Use the week days on the left of the leaf of the leap years marked with an underscore until 20 March 1. For the rest of the year use the one marked with the star on the following leaf or table. Turn the leaves having the months marked thereon as desired. For any year not given increase or diminish those already given 25 by four hundred. The device will preferably be made with a perforation *h* for the reception of a string or other device by means of which to hang it up.

Instead of arranging the monthly calendars 30 and the days of the week as shown in Fig. 1 they may be arranged as shown in Fig. 9 in which construction the book is simply turned around with the days and dates extending lengthwise the book instead of across it as in 35 the other form.

Other slight changes might be made in the arrangement of the parts of the device and in the details of construction without depart-

ing from the spirit of my invention or limiting its scope and hence I do not wish to limit 40 myself to the precise details of construction herein set forth, but,

Having fully described my invention, what I claim as new, and desire to secure by Letters Patent, is—

1. A perpetual calendar consisting of a series of tables containing figures indicating a series of years and also containing the names of the days of the week so arranged that they can be read in regular order on each table and 50 also across the series of tables and a series of monthly calendars adapted to be read with any of said tables, substantially as set forth.

2. In a perpetual calendar, the combination with a cover, of a series of monthly calendars 55 made in the form of a book and secured in said cover, a series of tables containing the dates of the days of the week and several series of years, made in the form of a book and secured to said cover, any table being 60 adapted to be read in connection with any monthly calendar, and said books being so arranged that when opened at a given place, the names of the days of the week will appear in line with the days of a certain month and 65 the years on the tables be covered by leaves of the book containing the monthly calendars, substantially as set forth.

In testimony whereof I have signed this specification in the presence of two subscr- 70 ing witnesses.

HENRY S. STEVENS.

Witnesses:

M. W. BOND,
JOHN H. MATTHEWS.
